UNITED STATES PATENT OFFICE.

ROSS F. GEORGE, OF SEATTLE, WASHINGTON.

SIGNAL AND DISPLAY LAMP.

Application filed February 14, 1922. Serial No. 536,438.

To all whom it may concern:

Be it known that I, Ross F. GEORGE, a citizen of the United States of America, and resident of the city of Seattle, in the 5 county of King and State of Washington, have invented certain new and useful Improvements in Signal and Display Lamps, of which the following is a specification.

My invention relates to a combined signal 10 and display lamp such, for instance, as are employed as the tail light or parking light of an automobile. While my lamp is peculiarly adapted for such use, I do not desire to be limited to this use only; for it may be 15 used to mark a dangerous turn in a roadway or for various other purposes.

It is an object of my invention to provide a lamp of the character described which has a light source therein, said light source 20 being visible in two directions and having also means for reflecting back light which enters it from an outside source.

A further object is the provision of means for holding and illuminating a display sign 25 or card in connection with a signal lamp.

A further object is the provision of a lamp having a display card or plate secured thereto, together with means for reflecting the light from the source within the lamp 30 upon the display card.

A further object is the provision of a reflector together with a transparent pane positioned in front of the reflector, the pane being of two or more different colors and 35 the reflector being so arranged to reflect light which enters through one color out through another.

My invention comprises those novel parts and combinations thereof which are shown 40 in the accompanying drawings, described in the specification, and particularly defined by the claims terminating the same.

In the accompanying drawings I have shown my invention in forms which are now 45 preferred by me.

Figure 1 is a rear elevation of my lamp.

Figure 2 is an axial longitudinal section therethrough.

Figure 3 is a transverse section there- 50 through taken on the plane of the light discharge slots.

Figure 4 is an elevation and Figure 5 is a longitudinal axial section through a modified form.

55 The casing 1 has two opposite signal apertures 10 and 11. These are closed by trans-

parent panes or, if desired, lenses may be substituted for these panes. I have shown the aperture 10 as closed by a lens 9 and the aperture 11 as closed by a pane 8. A light 60 source 2, consisting ordinarily of an electric light bulb, is suitably supported within the casing 1 and between the two apertures 10 and 11.

Within the casing 1, I may support an 65 inner casing 3 which is arranged to act as a reflector for light entering through the pane 8, to return it through the same pane. As shown herein the portion of the casing 3 farthest from the pane 8 terminates in a 70 truncated cone 30 which is open to permit discharge of light from the bulb 2 through the lens 9.

The pane 8 is provided with differently 75 colored areas, in the form shown in Figure 1, having a central circular area 81 of one color, as red, surrounded by a ring 82 of another color, or, for example, colorless, and outside of this a ring 83 which may be red. Light entering through the ring 82 80 will be reflected from the casing 3 and will come out through the circle 81, red. Light entering through the circle 81 or the ring 83 will naturally be reflected back red. In addition, all light from the bulb 2 will come 85 out red except that which passes through the ring 82, and this is so positioned that it is not seen ordinarily by an approaching observer.

I provide the casing 1 with means for de- 90 tachably securing a display plate thereto. This plate may be for the purpose of supporting the license tag, for illuminating a plate containing the name of the city of which the driver is a resident, or for other 95 purposes. I have shown a groove 17 which is crimped around the periphery of the casing 1 and into this groove the edge of a plate 4, which has been cut out to fit about the casing 1, is received. The outer casing 100 1 has peripheral slots 18 cut out adjacent the plate 4 and the metal 19 which represents the area of the slot may be conveniently bent outwardly therefrom to form a reflector for light coming from the source 105 2, or a separate reflector may be provided adjacent the slot 18. The inner casing 3 is likewise provided with peripheral slots 38. The metal 39 in this case may be removed or bent upward so that it does not interfere with the passage of light rays. The casing is shown in the accompanying draw- 110

ings as having an upper and a lower slot 18, the upper slot illuminating the name of the city which is placed upon the plate 4 and the lower slot permitting illumination 5 of the license plate 5 which may be supported upon the plate 4. By the means thus described I provide a positive illumination of the plate 4 and license plate 5 and do not depend upon light passing through the 10 slots and falling directly upon the plate, for the angle is such that very little light is thrown upon the plate unless it is reflected.

In Figures 4 and 5 I have shown a slightly 15 modified form of the device. The reflector 31 in this case is more nearly parabolic, so that light from the bulb 2 will be reflected therefrom and outward through the pane 8. The pane 8 in this case has the differently colored areas differently arranged. The central circle 84 is dropped to intercept what corresponds to the ring 85, which then takes the shape of a crescent. Thus all light issuing 20 from the crescent 85 is directed upward 25 above the level of the eye of an approaching observer and the signal will at all times appear red whether viewed by reflected light or by light emanating from the bulb 2.

I have shown the lamp as supported upon 30 a standard 6 which in turn is supported from the fender 7 of an automobile. It is evident that the manner of mounting or controlling the light is immaterial, as is the use 35 to which the lamp is put. It is ordinarily intended for use as a parking light, light from the source 2 passing through the lens 9 to warn a driver approaching from ahead, and both direct light from the bulb 2 and reflected light from the headlights of an approaching car warning a driver approaching 40 from the rear. If accidentally or intentionally the bulb 2 is turned off, reflected light alone will warn a driver approaching from the rear.

45 What I claim as my invention is:

1. A signal lamp casing having a periph-

eral slot for escape of light, with the metal representing the slot area bent outward to form a reflector for such escaping light, the casing having a peripheral groove parallel- 50 ing said slot and a display plate having an edge seating in said groove.

2. A signal light comprising an outer casing having opposite signal apertures and peripheral slots therebetween, an inner casing having apertures and slots registering with those of the outer casing, a light positioned between the two signal apertures within the inner casing, flanges formed of the material cut to form the slots of the outer 60 casing upstanding therefrom, to reflect light escaping through said apertures, and means for supporting an exterior sign upon the outer casing in position to be illuminated by such reflected light. 65

3. A signal comprising a casing having a view opening and a peripherally extending opening for escape of light, and having within itself a reflecting surface, a peripheral groove in the casing paralleling said peripherally extending opening, a light positioned within said casing to be reflected therefrom through the view opening and to shine through said peripherally extending openings, and a display plate having an 75 edge seating in said groove. 70

4. A signal comprising a casing having two opposite view openings and a peripherally extending opening for escape of light, and having a reflecting inner surface surrounding one view opening to direct light outward through the other, a light positioned within said casing and between said view openings and to shine through said peripherally extending opening, said casing 80 having exteriorly disposed means for supporting an object adjacent said peripherally extending opening at all points, to be illuminated by light shining therethrough. 85

Signed at Seattle, King County, Washington this 6th day of February 1922.

ROSS F. GEORGE.
